UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

MECHANISM FOR DISENGAGING AND ENGAGING THE MAIN GOVERNORS IN STEAM HOISTING-ENGINES.

1,327,633.

Specification of Letters Patent.

Patented Jan. 13, 1920.

Application filed December 24, 1917. Serial No. 208,714.

To all whom it may concern:

Be it known that I, EUGÈNE SCHNEIDER, a citizen of the Republic of France, and a resident of No. 42 Rue d'Anjou, Paris, and 5 Le Creusot, France, have invented a new and useful Mechanism for Disengaging and Engaging the Main Governors in Steam Hoisting-Engines, which invention is fully set forth in the following specification.

10 This invention relates to an apparatus which will allow of disengaging the governor of a steam engine, for example a hoisting engine, while running at full speed by acting upon the connection between the governor and the valve gear, the object being to provide an improved apparatus of this type.

The invention comprises an apparatus of this kind wherein in the transmission connecting the governor sleeve to the valve gear,

20 a device is provided which allows the governor to be disconnected from the valve gear and is characterized by the provision of means for actuating such device, which means effect at the same time the disconnection

25 of the governor from the valve gear and the return of that part of the transmission associated with the valve gear into a fixed position corresponding to the position of the valve desired.

30 In other words the improved apparatus according to the invention allows not only of disengaging in the known way the connection between the governor and the valve gear but also allows of returning at the same time the valve gear into the position corresponding to the low ball position of the governor at which position such a gear is locked.

This invention is illustrated in the accompanying drawings in its application, by way of example, to a puppet valve gear.

The general arrangement of the connection between the governor and the expansion gears is illustrated in Figure 1 which shows 45 the parts in their positions corresponding to the elevated position of the governor balls.

Fig. 2 is a corresponding sectional elevation showing the governor disconnected, and

50 Fig. 3 is a partial cross section on the line III—III of Fig. 2.

The valve gear which may be of any suitable type comprises in the example illustrated a suspension hook α for each valve formed at the end of one of the arms A of

a rocking beam A—A¹ pivoted at a fixed point A², the other arm A¹ of which carries a knife edge a^1 . This knife edge is acted upon by the knife edge b^1 carried by the arm B¹ of a catch lever B—B¹ pivoted at one end at B² to an eccentric rod C actuated by 60 a connecting rod and crank gear of the engine, and at its other end at B³ to a rod D which is in its turn connected to a connecting rod F by means of a bell crank lever E¹—E pivoted at a fixed point e. This connecting rod F is normally under the influence of the centrifugal governor. It influences the valve gear by displacing the fulcrum pin B³ of the catch lever B—B¹, A connecting rod F¹ connected to an arm E² 70 of the lever E—E¹, acts upon the other valve of the engine.

In Figs. 1 and 2, G is the sleeve of a ball governor of any known type of which it is unnecessary to give a detailed description, 75 since the present invention consists solely in the special connection between the sleeve G and the member (connecting rods F, F¹ or other members) which is under the control of this sleeve and by its movements influences 80 the valve gear of the engine.

According to this invention the said connection comprises a coupling which connects normally both portions of the connecting means, one portion ending at the governor 85 sleeve G and the other portion ending at the member D whose position which is variable by the action of the governor, influences the valve gear. H is a connecting rod belonging to that part of the connecting 90 means that remains constantly connected to the governor sleeve. F is a connecting rod belonging to that part of the connecting means that will remain permanently connected to the member D whose position influences 95 the valve gear.

The invention comprises a device which can be operated by hand or by power, and which allows of breaking or reestablishing at will the connection between the two 100 members or portions of the connecting means (in the example, between the connecting rods H and F). The same apparatus allows of causing the disconnection to be followed by a return and a locking of that 105 portion of the connecting means (member F) that is connected to the valve gear, into the position which it occupies normally

when the governor balls are in their lowest position.

In the example shown, the two members H and F are two connecting rods normally connected together by means of a shaft I arranged at right angles to the longitudinal axis of the engine, journaled in fixed bearings I¹ and having fixed on it a lever K which is connected to the member F, and a lever L with the free end of which the member H is adapted to engage.

It is to be understood that the shaft I may be common to two engines connected to the same governor and it may carry for this purpose, two levers K connected each to a member F actuating a corresponding device D.

The engagement of the connecting rod H with the lever L is effected normally by means of a fork H¹ which is formed on the connecting rod H, and which is arranged astride a roller L¹ carried by the end of the said lever L.

The disengaging mechanism comprises a member operable by hand or by power, and adapted in its travel to effect first a disengagement between the fork H¹ and the lever L, then the return of the lever L, and consequently the return of the shaft I and the connecting rod F, into the position they occupy when the governor balls are in their lowest position, so that the whole system which enables the governor to influence the valve gear, is from that moment placed out of operation by being locked.

In the example shown, the said disengaging member consists of a suitably guided stirrup M¹—M—M¹ the vertical limbs M¹ M¹ of which carry in bearings rollers M¹ by means of which they can raise the connecting member H and disengage the fork H¹ from the roller L¹. The base M of the stirrup is in its turn arranged to act upon the member F. For this purpose the lever L carries two arms N, N¹ provided each at its free end with a roller n, n¹.

By way of example, the stirrup M¹—M—M¹ is assumed to have been constructed for operation by compressed air. The base M is for this purpose fixed to a piston P working in a cylinder O which can be fixed on one of the brackets Q carrying the bearings I¹ of the shaft I. The branches M¹, M¹ of the stirrup are extended at their lower ends and are guided by means of these extensions M² in lugs O¹ formed in one piece with the cylinder O.

The governor being in the position shown in Fig. 1, then if it is supposed that the engine driver wishes to produce the disengagement, he turns the handle 1 of the distributing device 10 to open up communication between pipe 11 connected to a source of air under pressure and pipe 12 which leads to cylinder O thereby admitting com-

pressed air under piston P and causing it to ascend. The top roller m¹ of the left hand limb M¹ of the stirrup will first raise the connecting rod H until all connection between the latter and the lever L has been broken. This operation (which constitutes the disengaging operation proper) having been effected, then the base M of the stirrup will meet the roller n and will return the lever L toward the position corresponding to the "low ball" position of the governor. This position will be final when the stroke-limiting stops m² formed on the extensions M² will meet the lower lugs o¹ of the cylinder. But at that moment the roller n¹ will be depressed and would have also met the base M of the stirrup, so that any movement of the lever L is rendered impossible from that moment onward and the mechanism is thereby locked.

Fig. 2 shows the parts in the disengaged position; the fork H¹ of the connecting rod H being shown in dash and dot lines for the case where the engine is working, and in full lines for the case where the engine is stopped (low ball position).

The engagement of the governor must always be effected during its stoppage. There is no justification whatever for engaging the governor while it is working, because the disengaging operation is required only during purely special conditions of working and is necessary throughout the descent of the load. On the other hand it would not be prudent to couple the whole of the expansion gear suddenly to the governor while the latter is working, as such coupling would cause erratic movements of the governor sleeve, the effect of which would be to cause the engine to operate with periods of oscillation, the transmission of which would be extremely injurious to the hoisting cables.

The engaging operation is effected by connecting the cylinder O with the exhaust pipe 9 by turning handle 1 of the distributing device 10 in the proper direction. Under the action of the weight of the parts and of the counterweight P¹ provided on the end of the piston rod, the latter moves down, then releases first the rollers n and n¹, and then produces an engagement of the connecting rod H and the lever L. The extended limb h¹ of the fork H¹ is designed to promote this engagement.

Having now particularly described and ascertained the nature of my said invention and in what manner the same is to be performed, I declare that what I claim is:

1. In apparatus for disconnecting an engine governor, while running, from its valve gear, the combination of link members adapted to connect said governor and valve gear, and means independent of the governor acting in one direction to disconnect the governor from said valve gear and to re-

store the valve gear to a predetermined position and acting in the opposite direction to connect said link members.

2. In apparatus for disconnecting an engine governor, while running, from its valve gear, the combination of link members one of which connects at one end with said governor, the opposite end being provided with a fork, the other of said members being connected with said valve gear, a rocking member one arm of which is adapted to engage said fork, the opposite arm of which is pivotally connected to said valve gear link, and means movable into engagement with said governor link to disengage said fork from said rocking member and on further movement to tilt said rocking member and restore said valve gear to a predetermined position.
3. In apparatus for disconnecting an engine governor, while running, from its valve gear, the combination of link members one of which connects at one end with said governor, the opposite end being provided with a fork, the other of said link members being connected with said valve gear, a rocking

lever having side arms one end of said lever being adapted to engage said fork, the opposite end of said lever having a pivot connection with said valve gear link, and means for disengaging said links and for locking one of the same in a predetermined position comprising a movable head having limbs and means for moving said head into position for said limbs to lift said fork from engagement with said rocking member and on further movement for said head to engage said arms to lock the valve gear link in a predetermined position.

4. An apparatus as claimed in claim 3 wherein said movable head has a connection with a fluid-operated piston the piston rod of which is provided with a connected weight for facilitating descent of the piston and automatic releasing of said arms and reengagement of said links.

In testimony whereof I have signed this specification.

EUGÈNE SCHNEIDER.
